UNITED STATES PATENT OFFICE.

WILLIAM E. PRICE, OF WHITE PLAINS, NEW YORK, ASSIGNOR TO AURORA BEACON CORPORATION, OF NEW YORK, N. Y., A CORPORATION OF NEW YORK.

SIGN.

Application filed October 3, 1925. Serial No. 60,159.

This invention relates to display signs. An object of the invention is the provision of a sign of the character described having display or legendary matter thereon of novel 5 construction adapted to produce a highly artistic and attractive visual effect, by means and arrangement of parts capable of being provided at a comparatively low cost and yet resulting in highly practical and efficient 10 surface for the purposes described.

A further object of the invention is to provide a method for producing said improved sign which shall be capable of being very easily and cheaply carried out.

15 Other objects of this invention will in part be obvious and in part hereinafter pointed out.

The invention accordingly consists in the features of construction, combinations of 20 elements, and arrangement of parts which will be exemplified in the construction hereinafter described, and of which the scope of application will be indicated in the following claims.

25 In the accompanying drawing, in which is shown one of the various possible illustrative embodiments of this invention,

Fig. 1 is a front elevational view of a sign embodying the invention;

30 Fig. 2 is an enlarged cross-sectional view taken on line 2—2 in Fig. 1;

Fig. 3 is an enlarged cross-sectional view taken on line 3—3 in Fig. 1 showing the interior construction;

35 Fig. 4 is an enlarged detail view taken on line 4—4 in Fig. 3 showing the construction of the fabric forming the lettering;

Fig. 5 is a front elevational view of a sign having a modified form of sign plate embodying the invention;

40 Fig. 6 is an enlarged cross-sectional view taken on line 6—6 in Fig. 5; and

Fig. 7 is an enlarged detail view taken on line 7—7 in Fig. 6.

45 Referring in detail to the drawing, 10 denotes on electrically illuminated sign having a legend plate 11 embodying the invention. Said sign is seen to comprise a casing 12 constructed in any well known manner to

50 house an electric lighting fitting 13 and lamps 14, the latter being adapted to connect with a suitable power source (not shown) through conductor wires 15 for lighting the interior of the casing.

55 The legend plate 11 forms an enclosing

side of the casing, and preferably is made demountable to permit interchanging plates and the reversing thereof when the sign is constructed to be selectively used either suspended as shown in Fig. 1, or reversed and supported below as shown in Fig. 5.

The construction of the legend plate will now be described. In the form shown in Figs. 1 to 4 inclusive, a sheet 11^a of metal, fibre, composition or other suitable material is made of the proper size and shape to serve as the side wall of the casing 12, said material preferably being formed into a relatively stiff backing member.

A desired legend 11^b of plain or intricate 70 configuration in the form of letters, symbols or ornamentation is outlined or stencilled on said sheet and said legend cut out in any well known manner. A strip 11^c of flexible fabric such as textile fabric, 75 paper, or other like material which is translucent or may be made so, is applied to the rear side of the sheet 11, and portions 11^d of said strip are drawn through the cut-out portions of the back member to project 80 beyond the front side thereof, thus forming a raised or embossed protuberance. For artistic effect, the projecting or intaglio surfaces 11^d of said protuberances are preferably left uneven and irregular to simulate 85 rough cut stone. To secure the strip 11^c and intaglio surface 11^d in a fixed position, a suitable adhesive such as sodium silicate, shellac, varnish, lacquer, or other like substance is employed and preferably applied 90 to both sides of the strip. Thus the strip 11^c may be china silk, coated with sodium silicate S, the latter then also serving as a fire resistant. Shellac, varnish, or lacquer L may preferably be used in place of the 95 sodium silicate as an adhesive and coating where the sign is exposed to moisture. (See Fig. 7). To water-proof the strip a sodium silicate-coated strip, a surface coating of shellac, varnish, or lacquer L may be provided, as shown in Fig. 4.

Any of the aforementioned substances, when applied to the strip and dried is effective to stiffen the intaglio portions 11^d for retaining them in their proper shape, said 105 portions then forming what is commonly termed an "unbreakable" structure which is highly efficient as a light diffusing medium because of its texture.

For holding the unattached portion 11^e 110

of the backing sheet 11^a incorporated in the legend against accidental displacement, bowed bridging arms 16 are provided for anchoring said portion 11^c in alignment with 5 the rear side of said sheet, said arms being made of transparent material or of relatively thin wires which can cast only an imperceptible shadow across the translucent legend. As is clearly shown in Fig. 3, the 10 ends of said arms 16 are soldered or cemented to the rear side of said backing sheet 11^a and the portions 11^c in the well-known manner.

The interior of the backing sheet 11^a is 15 provided with a suitable light reflecting surface R, as for example white paint, or metallic foil, to increase the interior illumination of the sign. To produce colored lighting effects, the lamps 14 may be colored and 20 provided with automatic circuit-making and breaking means in the well understood manner, or slide holding means 17 may be provided on the rear side of the plate 11 for removably holding a color slide 17^a over 25 the cut-out portions of the backing member 11^a. The outer background surface of the plate 11 may be given any desired finish by painting, polishing, plating, engraving, or hammering to form a pebbled surface.

30 In Figs. 5 and 6 is shown a modified form of construction of plate 11. Here the outer back-ground surface is provided with a coating material 18 such as a textile fabric of velvet, silk, or the like material. Said 35 material is preferably secured to the plate by a suitable adhesive and the legend cut through prior to forming the intaglio portions as described above.

It is apparent that the sign 10 is very 40 practical since it can be easily, simply, and inexpensively fitted with legend plates incorporating styles of lettering to suit any individualistic taste and does not require expensive molding or other apparatus or 45 equipment for its construction.

Furthermore, the sign 10 when illuminated has also been found to be efficient to a high degree being legible from a relatively 50 large distance due to the fact that the rear side of the plate is smooth and even, is free from all projecting portions that might form shadows to obscure or blur the legend, and because the intaglio portions are formed of a translucent structure which is thin and 55 highly effective as a light diffusion medium.

Where signs in which the display or legendary portions are made to stand up from the back-ground, the cost of manufacture has been considerably high, particularly where 60 display portions comprise intricate figures, symbols, or designs which had first to be molded or otherwise formed and then applied to the body portion of the sign.

Briefly described, a dominant feature of 65 this invention is the simple means and

method for producing the raised effect accomplished as above described and whereby any complicated or intricate design may be artistically produced on the sign in a very cheap and highly effective manner.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:-

1. An article of manufacture comprising a sign having a backing plate, said plate having portions cut therefrom to form a legend, a flexible, pliable material drawn through said cut portions to project irregularly beyond the front surface of the plate to form an embossed pliable structure and means extending over said projected material for retaining said retained structure in a set position, said structure being entirely translucent and adapted to serve as a diffusion medium for light illuminating the rear side of said plate.

2. An article of manufacture comprising a sign having an opaque backing plate, said plate having portions cut therefrom to form a legend, members projecting away from the plane of the plate for retaining uncut portions of said plate in positions, a flexible material drawn through said cut portions to form a protuberance on the front surface of the plate, said members being formed of translucent material so as to be substantially non-shadow casting over said protuberance when said plate is illuminative and surface means for retaining said protuberance in a set shape.

3. In a sign, a backing plate having perforated portions forming a legend, a flexible, pliable material extending along the rear surface of the plate, portions of said fabric loosely projecting through the perforations beyond the front surface of the plate to form a raised irregular structure, and an adhesive coating for securing said fabric to the plate, said coating when dry serving to stiffen and retain said raised structure in a set position.

4. In a sign, a backing plate having perforated and detached portions forming a legend, a flexible material secured to the rear surface of the plate, portions of said fabric projecting through the perforations beyond the front surface of the plate to

form a raised structure, and a coating on said structure for stiffening and retaining the latter in a desired shape, and bowed bridge arms for holding said detached plate 5 portion against displacement anchored to the rear side of the plate.

5. The art of making a sign consisting in cutting out and detaching portions of a backing opaque plate to form a legend, 10 curing a flexible translucent sheet material against the rear side of said plate and drawing portions of the material through said

cut-out portions to form the legend as a protuberance on the front side of the plate, applying a film translucent coating to the 15 said protuberance for stiffening and retaining same in shape, and anchoring the detached portions to the rear side of the uncut portions of the plate, and surfacing the rear side of the uncut portions of the plate with 20 a light deflecting means.

In testimony whereof I affix my signature.

WILLIAM E. PRICE.
